ed to receive the jack and gradually lower the same as the latter is drawn in toward the burnishing-tool, and while the latter acts successively on the heel from its top-lift end to 5 ward the heel-seat, as set forth.

4. In a heel-burnishing machine, the jack and its slide-rod, combined with the lever a^6 , having a curved scroll-like finger, the said lever being movable substantially parallel with 10 the side of the jack, substantially as described.

In testimony whereof I have signed my name to this specification in the presence of two subscribing witnesses.

CHARLES J. ADDY.

Witnesses:

G. W. GREGORY,
W. H. SIGSTON.
